UNITED STATES PATENT OFFICE.

CHARLES F. J. CHARLISS, OF HOUSTON, TEXAS.

CULVERT.

1,334,484.

Specification of Letters Patent. Patented Mar. 23, 1920.

Application filed March 8, 1915. Serial No. 12,821.

To all whom it may concern:

Be it known that I, CHARLES F. J. CHARLISS, a citizen of the United States, residing at Houston, in the county of Harris and State of Texas, have invented certain new and useful Improvements in Culverts, of which the following is a specification.

This invention relates to new and useful improvements in culverts, which is also adapted to be used for sewers or other similar underground conveyers.

The object of the invention is to provide a culvert or sewer formed of sections of corrugated concrete, sheet metal or other suitable material, preferably arcuate in cross section, so that the sections will be nestable, which conduces to compactness in shipping the sections of which the culvert is formed.

Another feature of the invention resides in a structure whereby the sections may be jointed or united together in forming the culvert or sewer.

A still further feature of the invention resides in the provision of a structure of the character described formed of corrugated concrete or metallic sections adapted to be constructed into a culvert having two, three or more sides.

Finally the object of the invention is to provide a structure of the character described of maximum strength and minimum weight conducing to easy and inexpensive transportation and facilitating the handling and installing thereof.

With the above and other objects in view, the invention has particular relation to certain novel features of construction, arrangement of parts and use, an example of which is given in this specification and illustrated in the accompanying drawings, wherein:

Figure 1, shows a vertical sectional view of the culvert having three sides.

Fig. 2, shows an isometric view thereof.

Fig. 3, shows a plan view of three sides arranged in horizontal alinement, showing the connecting sutures and alternative schemes of reinforcing when used.

Fig. 4, shows a perspective view of one of the sections or slabs, showing a modified form of connecting sutures.

Fig. 5, shows a diagrammatic view of a two-sides structure suitable to be employed in a limited space.

Fig. 6, shows a diagrammatic view of a three-sided sewer arranged the reverse of the arrangement shown in Fig. 1.

Fig. 7, shows a diagrammatic view of a four-sided sewer or culvert constructed in accordance with this invention, and,

Fig. 8, shows an end view of the structure formed of sections of the character shown in Fig. 4.

Referring now more particularly to the drawings wherein like numerals of reference designate similar parts in each of the figures, the numerals 1, 1 and the numeral 2, refer respectively, to the side slabs and bottom slab of a section of a sewer or culvert, said slabs being transversely corrugated and slightly curved or arcuate in cross section, so as to conduct to great strength in proportion to the weight of the slab and the amount of material therein. As shown, these slabs are formed of concrete, but sheet metal or any other suitable material may be employed. The adjacent edges of the slabs or plates forming the respective sides of the structure, are joined, preferably, by straight shoulder and tenon 3 and 4, forming sutures, and these joints are held in position by means of the pressure of the surrounding earth and strength is added to the structure by arranging the respective side slabs so as to break joints, as illustrated in Fig. 3.

As shown in Figs. 4 and 8, a modified form of joint is employed, wherein the interlocking parts have lengthwise orifices, as 5, arranged in alinement when the slabs are placed in position, and provided to receive locking rods, as 6, for securing the slabs in position.

It is obvious that an arch effect, and the strength given thereby will be obtained in this structure, as is illustrated more accurately in Figs. 1, 2, 6 and 8.

When the slabs are formed of concrete they should be reinforced with steel rods, as 7. These reinforcements are so located in the slab, as to give the maximum amount of strength, some of the rods passing over the ribs or corrugations and their ends terminating in the respective troughs on the opposite sides of the corrugations over which they pass. These rods reinforce the sides against bulging laterally, as a result of the vertical pressure sustained by the sewer from above. The other rods each span a trough between two corrugations, beginning at one end of one corrugation and terminating in the opposite end of the other corrugation. These rods reinforce the sides

of the culvert against being pressed inwardly by lateral pressure. Other forms of reinforcing may be employed, either transverse reinforcing rods, reinforcing mesh or such other forms as may be desired; and it is further to be observed that reinforcing is not indispensable and in many cases the culvert may be constructed without reinforcement of any character.

10 What I claim is:

1. A culvert, formed of a plurality of arched slabs, corrugated in longitudinal section, said slabs having interlocking edges, the interlocking parts being set back from the corresponding edges of the slabs and longitudinal locking rods passing through

said interlocking parts and securing them together.

2. A culvert, formed of arched slabs, the adjoining edges of said slabs being united 20 by tenon and mortise sutures, which are set back from the respective edges of the slabs and means for securing said interlocking parts together.

In testimony whereof I have signed my 25 name to this specification in the presence of two subscribing witnesses.

CHARLES F. J. CHARLISS.
